UNITED STATES PATENT OFFICE.

CHARLES E. GODLEY, OF DETROIT, MICHIGAN, ASSIGNOR TO EDMUNDS & JONES CORPORATION, OF DETROIT, MICHIGAN, A CORPORATION OF NEW YORK.

LAMP-DOOR FASTENING.

Application filed December 11, 1925. Serial No. 24,678

My invention relates to means for connecting a detachable door or lens front to the body of a lamp, and for this purpose aims to provide simple and easily manipulated fastening means which will yieldingly press the door inwardly of the lamp body to afford a tight seal between the reflector and the lens of the lamp, and which will positively force the door off the lamp body when the fastening means are manipulated for releasing the door.

Furthermore, my invention provides a construction of this general type which can readily be applied to lamp doors of standard types and which will only require simple lugs or ears upon the lamp body. It also provides a door fastening arrangement in which the portions carried by the door can be made so small as to be comparatively inconspicuous, in which these portions can be assembled as units before attaching the same to the door, in which this attaching can easily be accomplished by merely providing suitable lateral perforations in the door, and in which a single and simple auxiliary fastening element will suffice for rigidly securing each such assembled unit to the door.

Still further and also more detailed objects will appear from the following specification and from the accompanying drawings, in which

Fig. 1 is a front elevation of an automobile head light equipped with fastening means embodying my invention.

35 Fig. 2 is an enlarged and fragmentary section taken radially and longitudinally of the lamp along the line 2-2 of Fig. 1.

Fig. 3 is a similar section taken when the screw is almost entirely unscrewed from the adjacent lug or ear on the lamp body and showing how the door is pushed off the lamp body.

Fig. 4 is a fragmentary section through the door of the lamp, taken along in the same radial plane as Fig. 2, with the attaching unit shown in elevation in a position occupied by it while it is being attached to the door.

Fig. 5 is an enlarged perspective view of the shell of one of the attaching units.

Fig. 6 is a similarly enlarged bottom view of this shell.

Fig. 7 is a similarly enlarged section taken along the line 7-7 of Fig. 3 through one

of the attaching units and the adjacent 55 peripheral wall of the lamp door.

In the illustrated lamp, the body includes a peripheral wall 1 provided at its forward end with an inwardly directed flange or shelf 2 upon which the edge flange 3 of the reflector 4 is seated, and this reflector is provided at its mouth with an annular groove 5 into which a packing ring 6 is cemented. The door of the lamp includes a lens 7 gripped between the inner edge of the frontal portion 8 of a lens ring and clamping fingers 9 secured to the inner or rear face of this frontal portion. The peripheral part 10 of this lens ring is recurved at its rear end to provide a relatively short annular portion 11 of a bore corresponding to the outside diameter of the peripheral body wall 1 and hence adapted to be slid upon the latter.

Projecting radially outward from the body wall 1 and desirably spaced uniformly from the shelf 3 are a plurality of lugs or ears 12 which preferably are uniformly spaced circumferentially of this wall. Each of these ears 12 is rigidly secured to the said wall, as for example by extending it through a suitable perforation in this wall, and having its inner portion 12^a extend rearwardly, and welding this portion 12^a to the said wall.

These ears constitute fastening elements on the lamp body for cooperating with yieldingly mounted screws 13 supported by the door of the lamp, each of these screws being slidably mounted in a screw guide secured to the peripheral wall 10 of the lens ring. As here illustrated, each screw guide is formed of a single piece of sheet metal which has its medial part bent into a tubular portion 14 having a bore slidably fitting the head 13^a of the screw mounted in that guide, and having its rear end contracted to afford a ledge 15 of a bore slightly larger than the diameter of the shank of the screw. The tubular portion 14 desirably extends for more than 180 degrees about the axis of the

more than 180 degrees about the axis of the screw and the free end parts 16 of the metal-blank are disposed parallel to each other so as to form projecting arms as shown in Fig. 5. The lens ring wall 10 is provided adjacent to each screw guide with a perforation 17 corresponding in width to the distance between the oppositely directed faces of the arms 16. Each of these arms has at its forward end and adjacent to the tubular

portion 14 a notch 18 corresponding approximately to the thickness of the lens ring wall 10, and each arm tapers in length towards its free end substantially along an arc 5 having the bottom of the notch 18 as its center, while the length of each arm 16 adjacent to the tubular portion 14 corresponds to the length of the said perforation 17.

With the screw guide thus constructed, the 10 arms can be inserted through the adjacent perforation 17 by initially tilting the guide and permitting the notch 18 to hook into the forward edge of the perforation, as shown in Fig. 4. The guide is then swung about 15 its said hooking engagement with the lens ring to dispose the axis of the tubular portion 14 parallel to the axis of the lamp and to cause the rear outer ends of the arms 16 to seat on the rear wall of the said perforation, after which the guide is secured in 20 this position by inserting a spring cotter 19 which extends through aligned perforations 20 in the arms 16 and which engages the inner face of the peripheral lens ring wall 25 10.

Interposed between the head 13^A of each screw and the rear end ledge 15 of the corresponding guide is a compression spring 21, which continually urges the screw forward- 30 ly of the lamp or away from the adjacent ear. Extending transversely through the shank of each screw behind the guide is a stop member, such as a spring cotter 22 which is disposed for engaging the rear end 35 of the guide to limit the forward movement of the screw when the screw is unscrewed either entirely, or at least to a considerable extent from the adjacent ear 12 through which the screw is threaded when the door 40 is attached.

When the door is detached, this cotter 22 prevents the screw from being ejected by the associated spring, so that the screw will not be lost. In attaching the door, this is 45 slipped upon the lamp body with the screw guides in alignment with the ears and the screws are then tightened, the guides being desirably of such a length that each screw head projects beyond its forward end when 50 the screw is loose, so as to make the screw easier to reach with a screwdriver. During the tightening of each screw, this rotates freely until the lens engages the packing ring 6 on the reflector, the location of the 55 ears and guides being such that this engagement occurs when each guide is still at a considerable distance from the ear aligned with it. Then a further rotation of the screw in its attaching direction compresses 60 the spring 21, as the packing ring prevents a further rearward movement of the door. This compression continues until the cotter 22 (which in effect is a lateral projection on the shank of the screw) engages the ear 12. 65 By suitably proportioning the parts, I cause

this stopping of the attaching movement of the screw to occur while the spring is only partially compressed, thereby causing the door to be yieldingly clamped to the lamp body and permitting the springs to compensate for variations in the thickness of the lens, the compression of the packing ring and the exact assembly of the guides and ears with respect to the lamp parts which carry these. In practice, the screws, springs and stop cotters 19 can be assembled with the screw guides as units (after the manner shown in Fig. 4) before attaching each such assembly to the door, thereby facilitating the assembling and permitting a single size of such attaching units to be used economically with lamp doors of various sizes and types.

However, while I have illustrated and described my invention in an embodiment including a screw guide formed of a single piece of sheet metal, I do not wish to be limited to this or other details of the construction and arrangement here disclosed, it being obvious that many changes might be made without departing either from the spirit of my invention or from the appended claims.

I claim as my invention:

1. In a lamp, a forwardly open casing, a door movably disposed at the mouth of the casing, an ear projecting radially outward from the casing adjacent to its mouth, a screw guide projecting radially outward from the door in front of the ear and in alignment with the ear longitudinally of the casing, a screw slidably mounted in the guide and threaded into the ear, a compression spring operatively interposed between the screw and the guide for urging the spring forwardly, means associated with the door and casing for limiting the rearward movement of the door with respect to the casing to a position in which the guide is spaced from the ear, and stop means carried by the screw for engaging the ear to limit the threading of the screw into the ear to an extent insufficient for fully compressing the spring.

2. The combination with a lamp casing, and with a door fitting the mouth of the casing and having a peripheral wall, of door fastening means, comprising an ear projecting outwardly from the casing adjacent to its mouth, a screw guide projecting outwardly from the door in alignment with the ear, a screw slidably mounted in the guide and threaded into the ear, a compression spring operatively interposed respectively between the screw and the guide for urging the screw away from the ear, the guide having a pair of arms extending through the peripheral wall of the door and having a portion engaging the outer face of that wall, and a fastening element extend-

- ing through the said arms and engaging the inner face of that wall.
3. A lamp construction as per claim 2, in which the peripheral door wall has a perforation through which the said arms are slidably insertible, and in which each arm is undercut at one edge to provide a hooking engagement with a part of the said wall adjacent to the perforation.
- 10 4. A lamp construction as per claim 1, in which the door has a peripheral wall provided with a perforation in longitudinal alignment with the ear on the casing; and in which the screw guide is constructed of a single piece of sheet metal formed to afford a peripherally incomplete tubular portion and a pair of arms both extending through

the said perforation, the tubular portion having a forward part slidably housing the head of the screw and having at its rear end 20 a ledge engaged by one end of the spring.

5. A lamp construction as per claim 1, in which the stop means are also disposed for engaging the guide upon incomplete unscrewing of the screw from the ear, so as to 25 limit the forward movement of the screw with respect to the guide by the spring and so as to cause the stop means to force the door forwardly away from the ear during the completion of the unscrewing of the 30 screw from the ear.

Signed at Detroit, Michigan, December 3, 1925.

CHARLES E. GODLEY.
